H. L. ALGERMISSEN.

BALL CASTER.

APPLICATION FILED MAY 21, 1912.

1,053,895.

Patented Feb. 18, 1913.

UNITED STATES PATENT OFFICE.

HENRY L. ALGERMISSEN, OF PROSPECT HILL, MISSOURI, ASSIGNOR OF ONE-HALF TO
WILLIAM T. FARRELL, OF ST. LOUIS, MISSOURI.

BALL-CASTER.

1,053,895.

Specification of Letters Patent. Patented Feb. 18, 1913.

Application filed May 21, 1912. Serial No. 698,852.

To all whom it may concern:

Be it known that I, HENRY L. ALGERMISSEN, a citizen of the United States, and resident of Prospect Hill, St. Louis county, Missouri, have invented certain new and useful Improvements in Ball-Casters, of which the following is a specification containing a full, clear, and exact description, reference being had to the accompanying drawings, forming a part hereof.

My invention relates to improvements in ball casters, and the object of my invention is to construct a caster body in cup form arranged to receive a large ball and a number of small balls, a retaining ring and a member arranged to be secured to the article to be supported by the caster, all of sheet metal, and to provide integral means whereby the parts of the caster may be assembled 10 and secured at a minimum of cost.

With the above purposes in view my invention consists in certain novel features of construction and arrangement of parts as will be hereinafter more fully described, 15 pointed out in the claims and illustrated by the accompanying drawings, in which—

Figure 1 shows in elevation a caster constructed according to my invention; Fig. 2 is a vertical, sectional elevation of the 20 caster; Fig. 3 is an inverted plan of the caster; and Fig. 4 is a vertical, sectional elevation of one of my improved casters having a plate for attachment to the article to be supported, Figs. 1 and 2 being the type 25 having stems to fit in sockets.

Referring by numerals to the accompanying drawings: 5 designates the cup shaped body portion of the caster having formed integral therewith a conical stem 6 provided with a shoulder 7. On the lower rim or margin of the cup shaped body portion 5 there is formed a plurality of spaced apart 30 projections 8.

9 designates the ball cup which is shaped 45 to fit within the body portion 5 of the caster, and is provided at its lower end with an annular flange 10 which is perforated at 11, the number and spacing of the perforations being the same as the number and spacing 50 of the projections 8 of the cup shaped body portion 5.

12 designates a ring which is perforated at 13 coincident with the perforations 11 in the flange 10 of the cup 9. The ring 12 is pro-

vided at its inner periphery with a substantially right angled depending flange 14.

15 designates a plurality of balls which are arranged to engage in rolling contact with the inner surface of the cup 9 and with each other, and upon the upper surface of 60 the ring 12.

16 designates a ball of much greater size than the balls 15 which is placed in a position to engage with each of the balls 15 and is retained in position in engagement with 65 said balls 15 by the depending flange 14 of the ring 12. It is to be observed that the upper surface of the ring 12 is on a line above the center of the large ball 16 in order that the friction between the small balls 15, 70 the cup 9 and large ball 16 is reduced to a minimum. It is to be observed further that the lower end of the flange 14 extends below the center of the large ball 16, thereby retaining the large ball in position so that, 75 when the article which is supported by the caster is elevated from the supporting surface, the large ball 16 will not be dropped from the caster proper.

In Fig. 4 the stem 6 of the body portion 80 has secured thereto a plate 17 having screw holes therethrough in order that the caster may be secured to articles of furniture not having socket holes.

All of the parts entering into the construction of my improved caster are each struck from single pieces of sheet metal, and the integral securing devices form a means whereby the parts may be held in assembled form, the assembling being facilitated and 90 the cost of construction being reduced to a minimum.

For the reason that the upper surface of the ring 12 is above the center of the large ball 16 crowding of the small balls 15 is 95 prevented.

The assembling of the parts is most advantageously accomplished by holding the cup-shaped body portion 5 in an inverted position. The ball cup 9 is then placed 100 within the cup-shaped body portion 5, the spaced apart projections 8 of the body portion 5 extending through the perforations in the annular flange 10 of the ball cup 9. The proper number of balls 15 are then 105 placed into the cup 9. The large ball 16 is then placed in position, which placing properly distributes the balls 15 in the cup

9. The retaining ring 12 is then placed in position with its perforations over the ends of the projections 8. The depending flange 14 of the said ring 12 is of such shape that it will pass over the large ball 16 to a point approximating the greatest diameter of the larger ball. This completes the assembly of the caster, except for the bending or clenching of the projections 8, which is accomplished by simply striking each projection with a hammer or other tool.

I claim:

1. In a caster, a cup shaped body portion having integral spaced apart projections 15 from its lower margin, a cup having a perforated flange, a perforated ring having a depending flange, said projections arranged to be inserted through said perforated flange and perforated ring and clenched, a 20 large ball arranged to be held in place by said depending flange, and a plurality of small balls arranged for rolling contact with said large ball and with said cup.

2. A caster, comprising a cup shaped body 25 portion having an integral hollow stem, and integral projections at its lower margin, a cup arranged to contain a quantity of small balls, and a retainer having a depending flange arranged to hold in place a large ball,

said projections on the lower margin of the 30 body portion arranged to secure the cup and the retainer to the body portion.

3. A caster, comprising a large ball and a number of small balls in rolling contact therewith, a cup arranged to engage with 35 the small balls, a body portion embracing said cup and provided with means for attachment with an article to be supported, a retaining ring for the smaller balls having its upper surface above the center of the 40 larger ball, an integral depending flange on said ring having its lower end beneath the center of the large ball in order to secure the large ball in place, a flange formed integral with said cup, there being perforations 45 in said flange and in said ring, and integral projections carried by the body of the caster arranged to be inserted through said perforations and clenched to secure the parts of the caster together.

In testimony whereof, I have signed my name to this specification, in presence of two subscribing witnesses.

HENRY L. ALGERMISSEN.
